COIN BANK

Jerome B. Aronson, Frank Kusch, and Joseph L. Eisendrath, Jr., Chicago, Ill., assignors to Banthrico, Inc., Chicago, Ill., a corporation of Illinois

Application July 5, 1938, Serial No. 217,456

5 Claims. (Cl. 194—1)

The present invention relates to containers and is more particularly concerned with the type of containers commonly referred to as coin banks.

The present invention is shown as applied to a coin bank of the type having means whereby to visually indicate the deposit of a coin by actuating indicator dials which show the day and the month.

It is the purpose of the present invention to provide certain novel improvements in a coin bank of this character whereby to simplify manufacture thereof and to improve the operation of the indicating means.

Among other objects, the present invention contemplates the provision of a novel end closure construction for the receptacle. The novel end closure construction is so arranged as to cooperate in a novel way with an indicator dial mounting frame to accurately position the mounting frame within the coin receptacle.

The present invention contemplates also the provision of a novel construction whereby the indicating dials may be reset by the use of a key or a suitable pointed instrument. This and other features and advantages of the invention will appear more fully from the following description and accompanying drawings wherein a preferred form of the invention is shown. It is to be understood, however, that the drawings and description are illustrative only, and are not to be taken as limiting the invention except insofar as it is limited by the claims.

In the drawings:

Fig. 1 is a vertical sectional view through a coin bank embodying the invention;

Fig. 2 is a bottom plan view of the structure shown in Fig. 1;

Fig. 3 is a sectional view taken on the line 3—3 of Fig. 1;

Fig. 4 is a sectional view on the line 4—4 of Fig. 1;

Fig. 5 is a fragmentary perspective view of a portion of the dial supporting frame illustrating the coin guides employed;

Fig. 6 is a fragmentary perspective view of a portion of the dial supporting frame;

Fig. 7 is a perspective view of a cam plate forming a part of the dial structure;

Fig. 8 is a fragmentary perspective view of a portion of the bottom of the coin bank;

Fig. 9 is an enlarged fragmentary view taken substantially on the line 9—9 of Fig. 1;

Fig. 10 is an enlarged fragmentary view taken on the line 10—10 of Fig. 1; and

Fig. 11 is a fragmentary view in side elevation

of a portion of the coin bank showing the windows through which the dial indicators are visible.

Referring now to the drawings, the present invention is embodied in a coin bank of the general type wherein a receptacle 1 is provided with a coin receiving slot 2 at one end and a hinged closure 3 at the other end. The receptacle 1 contains a frame 4 which supports a plurality of dials 5 and 6. The dial 5 has the numbers one to thirty-one thereon and the dial 6 has the months arranged thereon in sequence. The receptacle 1 as shown in Fig. 11 has two windows 7 and 8 cut therein so that the indicators on the dials 5 and 6 are visible through these windows.

Means are provided whereby the insertion of a coin through the coin slot 2 is caused to rotate the dial 5 one step each time a coin is inserted to bring a new number before the window 7 in the receptacle 1. Each time the dial 5 makes a complete revolution, it is coupled with the dial 6 in a manner which will be later described. The dial 6 is then turned one step with the dial 5 to change the month indicator visible through the window 8 in the receptacle 1. With this general explanation of how the device operates, the novel features of the bank together with the mechanical construction of the several parts will now be described.

The receptacle 1 is desirably constructed of a composition material which may be readily molded such, for example, as the synthetic resin materials sold under the trade name of "Bakelite." To facilitate the use of the molded receptacle of this type, we have provided a novel end closure construction for supporting the hinged closure 3. The receptacle 1 has an outwardly extending flange 9 at the bottom thereof which flange provides a shoulder 10. Outside of the shoulder 10, the flange 9 is turned down to provide a supporting rim 11. The supporting rim 11 is provided with inwardly extending lugs 12, 13, 14 and 15. These lugs are separated from the flange 9 by narrow slots such as are indicated at 16 (see Fig. 8). Also each lug has an opening 17 therethrough which extends from the bottom face of the lug to the slot 16.

The end closure 3 is made up of three sections. One section 18 consists of a metal plate which is shaped to slide beneath the lugs 14 and 15 and abut against the end portion of the rim 11. The plate 18 is secured in position so that it cannot be withdrawn by punched portions 19 and 20 of the metal extending into corresponding depressions 21 (see Fig. 1) formed in the shoulder 10. To

further secure the plate 18 in position an L-shaped metal strip 22 is riveted to the plate 18 and is riveted to the wall of the receptacle 1 above the flange 9 (Fig. 1). The plate 18 has bearings 23 and 24 for a hinge pin 25 by which a plate 26 is hinged to the plate 18. In addition, the plate 18 has a flange 27 (Figs. 1 and 4) turned up and slotted at 28 to receive the lower edge of the frame 4.

The plate 26 carries a lock 29 and is provided with a coin receiving slot 30 protected by guards 30a and 30b. The plate 26 is wide enough to bear against the shoulder 10 and extends from the hinge pin 25 to the lugs 12 and 13.

A plate 31 fits in the slots 16 beneath the lugs 12 and 13 and extends against the flange 11 as shown in Figs. 2 and 8. This plate is secured by punched up portions 32 and 33 thereof extending into corresponding depressions 34 formed in the shoulder 10. An angle strip 35 is riveted to the receptacle 1 and to the plate 31 (Figs. 1 and 2) to further secure the plate 31 against removal. It is obvious, of course, that if desirable, the plates 18 and 31 may be secured by the punched up portions 19, 20, 32 and 33 alone or by the strips 22 and 35 alone. Where it is desired to have the plates 18 and 31 removable, they may be secured by the punched up portions alone and can then be pulled out.

The plate 31 has an upturned flange 36 which is utilized as a stop for a latch 37 of the lock 29. The details of the lock 29 are old and well known in this art and therefore have not been shown. The flange 36 is also slotted as shown at 38 in Fig. 8 to receive the lower edge of the frame 4 and thus position the latter in spaced relation to the adjacent side wall of the receptacle 1. The frame 4 is positioned at the top thereof by a flange 39 on the frame 4 and depending lugs 40, 41 and 42 (see Figs. 1 and 3) on the receptacle 1. There is no direct connection between the frame 4 and the receptacle 1. However, it is firmly held in place by means of the flanges 27 and 36 and the lugs 40, 41 and 42.

Referring now to the mechanism by which the dials 5 and 6 carried by the frame 4 are to be operated, all of this mechanism is carried by the frame 4. The frame 4 has a coin guide 43 (Fig. 5) struck out from the body thereof. The guide 43 has a depending flange 44 so as to direct the coin downward after it is inserted into the coin receiving slot 2. Opposite the flange 44, a movable coin guide 45 (Fig. 5) is carried by a lever 46 (Figs. 1 and 5). The lever 46 is pivoted on the frame 4 in the manner shown in Fig. 9. The lever 46 is provided with an aperture which receives a bearing boss 47 which is struck out from the material of the frame 4.

A second lever 48 is pivoted on the frame 4 by a bearing boss 49 which is like the bearing boss 47. The lever 48 is biased downward at one end by a spring 50 hooked over the end of the lever in notch 51 and held at its other end by a finger 52 struck out from the frame 4. The lever 48 extends beneath a turned out lug 53 on the lever 46. The lug 53 is so positioned that when the lever 48 is pushed out by the pressure of the coin against the coin guide 45, the lever 48 is turned clockwise against the pull of the spring 50 which is under tension.

The lever 48 has a push rod 54 pivoted thereon by bearing boss 55. The push rod 54 extends downwardly between a finger 56 on the frame 4 and a spring 57 which is secured on a side flange

58 of the frame 4. At its lower end, the push rod 54 has a flange 59 that is adapted to engage ratchet teeth 60 on the dial 5. Each time the lever 48 is turned clockwise by a coin being inserted through the slot 2, the flange 59 engages one of the ratchet teeth 60 and turns the dial 5 far enough to bring a new number in front of the window 7.

The mounting of the dials 5 and 6 on the frame 4 is such that they are held together under spring pressure with a sufficient force that they can be turned by means of the push rod 54 but they will remain in place when so turned. This mounting will now be described.

The frame 4 is impressed to provide a raised bearing surface 61 (see Figs. 3 and 6). The dial 5 has a central portion 62 which is offset with respect to the rim portion thereof so as to bear against the surface 61. Circular guides 63 and 64 (see Fig. 6) are struck up from the frame 4 and have inturned lugs 65, 66, 67 and 68. A cam plate 69 shown in detail in Fig. 7 has a central depressed portion 70 provided with two apertures 71 and 72 to receive the guides 63 and 64. A web 73 fits between the lugs 65 and 66 on one side and 67 and 68 on the other side. The cam plate 69 has a raised detent 74 thereon and has a notch 75 cut in the rim thereof. The depressed portion 70 of the cam plate 69 rests directly upon the portion 62 of the dial 5.

The dial 6 has a central aperture 76 and is depressed around this aperture as indicated at 77 in Fig. 3 so as to fit within the depression 70 of the cam plate 69. The dial 6 has a plurality of small apertures 78, one for each month appearing thereon. The apertures 78 are arranged so as to be in line with the detent 74 which rests in one of the apertures 78 except during the time when the dial 6 is being turned. A spring 79 fits within the depressed portion of the dial 6 and is held in place by a rivet 80 which extends through the spring and through plate 81 that covers the aperture left in the frame 4 by the punching up of the guides 63 and 64. The spring 79 supplies the necessary tension to hold the dials in assembled position upon the frame 4. The dial 6 is provided with ratchet teeth 82 in its periphery as shown in Figs. 1 and 3.

In order to operate the dial 6 from the dial 5, there is provided on the dial 5 a spring control pawl 83 shown in dotted lines in Fig. 1. This pawl is pivoted on the dial 5 by a suitable boss 84 struck up from the dial 5. A spring wire 85 is fixed to the dial 5 at 86 and engages a tail piece 87 on the pawl 83. This tail piece is grooved at 88 as shown in Fig. 10 to receive the free end of the wire 85. At the end of the pawl 83 opposite the tail piece 87, there is provided a finger 89 which extends across the edge of the cam plate 69 and beyond the dial 6 (see Fig. 3). When the finger 89 is riding upon the circular periphery of the cam plate 69, it is held out of engagement with the teeth 82 of the dial 6. However, when the finger 89 drops into the notch 75 of the cam plate 69, it engages one of the teeth 82 on the dial 6 and can then move. Then when the dial 5 is moved by the push rod 54, the dial 6 also will be moved by the finger 89 and the detent 74 will be moved out of one aperture 78 into another aperture 78 to thus change the month reading through the opening 8 in the receptacle 1.

The difference in the number of days per month makes it necessary at certain times to re-

adjust the dials 5 and 6 by moving them by hand. To make them readily accessible through the opening provided by the closure plate 26, the depression in the frame 4 which provides the bearing surface 61, extends to the lower edge of the frame as shown at 90 (see Figs. 1 and 6). The dials are adjusted by inserting a key for the lock 29 up through the opening provided by the depression 90 where it can be engaged with the teeth 60 to advance dial 5 a sufficient number of spaces to cause the finger 89 to drop into the slot 75 and bring a new month and a new day into position without operating the coin control lever 45. For example, the dial 5 contains 31 teeth and has a day number for each tooth; thirty-one days in all. The month of February has 28 or 29 days. Therefore, when the dial reading for this month reads 28, or 29 if it is leap year, the bank is opened and the dial 5 is turned by engaging the key into the periphery thereof until the finger 89 drops into position behind a tooth 82 of the dial 6. The dial 5 is then pushed one step further by the key to move both dials 5 and 6 and bring a new month and new day number before the openings 7 and 8 in the receptacle 1.

From the above description, it is believed that the construction and operation of this device will be readily apparent to those skilled in this art.

Having thus described our invention what we claim as new and desire to secure by Letters Patent is:

1. In a coin bank, a dial-carrying frame, said frame comprising a sheet having a circular dial-receiving depression in one side, a cupped dial plate seated in said depression whereby to be guided in its rotation by said depression, said plate having a peripheral flange provided with ratchet teeth, said flange providing a number-receiving surface, a fixed cam plate within the cupped dial plate and bearing thereon, a second dial plate bearing on said cam plate and having ratchet teeth thereon, said second dial plate having indicia thereon spaced to correspond to the spacing of the ratchet teeth of said second dial plate, said frame having curved guide portions extending through said plates at the center of said depression, the said dial plates being provided with central openings whereby they are rotatable on said guide portions, means engaging the teeth of the first named dial plate for turning it, and a pawl on the first named dial plate cooperating with the teeth of the second dial plate and with the cam plate to advance the second dial plate once for each rotation of the first named dial plate.

2. In a coin bank, a dial-carrying frame, said frame comprising a sheet having a circular dial-receiving depression in one side, a cupped dial plate seated in said depression whereby to be guided in its rotation by said depression, said plate having a peripheral flange provided with ratchet teeth, said flange providing a number-receiving surface, a cam plate within the cupped dial plate and bearing thereon, a second dial plate bearing on said cam plate and having ratchet teeth thereon, said second dial plate having indicia thereon spaced to correspond to the spacing of the ratchet teeth of said second dial plate, said frame having curved guide portions extending through said plates at the center of said depression, the said dial plates being provided with central openings whereby they are rotatable on said guide portions, said cam

plate having a portion extending between the guide portions to prevent rotation of the cam plate, means engaging the teeth of the first named dial plate for turning it, and a pawl on the first named dial plate cooperating with the teeth of the second dial plate and with the cam plate to advance the second dial plate once for each rotation of the first named dial plate.

3. In a coin bank, a dial-carrying frame, said frame comprising a sheet having a circular dial-receiving depression in one side, a cupped dial plate seated in said depression whereby to be guided in its rotation by said depression, said plate having a peripheral flange provided with ratchet teeth, said flange providing a number-receiving surface, a fixed cam plate within the cupped dial plate and bearing thereon, a second dial plate bearing on said cam plate and having ratchet teeth thereon, said second dial plate having indicia thereon spaced to correspond to the spacing of the ratchet teeth of said second dial plate, said frame having curved guide portions extending through said plates at the center of said depression, the said dial plates being provided with central openings whereby they are rotatable on said guide portions, a spring holding said plates in the circular depression of said sheet, means engaging the teeth of the first named dial plate for turning it, and a pawl on the first named dial plate cooperating with the teeth of the second dial plate and with the cam plate to advance the second dial plate once for each rotation of the first named dial plate.

4. In a coin bank, a dial-carrying frame, said frame comprising a sheet having a circular dial-receiving depression in one side, a cupped dial plate seated in said depression whereby to be guided in its rotation by said depression, said plate having a peripheral flange provided with ratchet teeth, said flange providing a number-receiving surface, a cam plate within the cupped dial plate and bearing thereon, a second dial plate bearing on said cam plate and having ratchet teeth thereon, said second dial plate having indicia thereon spaced to correspond to the spacing of the ratchet teeth of said second dial plate, said frame having curved guide portions extending through said plates at the center of said depression, the said dial plates being provided with central openings whereby they are rotatable on said guide portions, means engaging the teeth of the first named dial plate for turning it, and a pawl on the first named dial plate cooperating with the teeth of the second dial plate and with the cam plate to advance the second dial plate once for each rotation of the first named dial plate, said pawl having a tail piece provided with a groove and a spring on said first named dial plate riding in the groove to hold the pawl against the cam plate.

5. In a coin bank, a dial-carrying frame, said frame comprising a sheet having a circular dial-receiving depression in one side, a cupped dial plate seated in said depression and having a peripheral flange provided with ratchet teeth, a cam plate bearing on said dial plate, a second dial plate having ratchet teeth and bearing on said cam plate, said second dial plate having indicia thereon spaced to correspond to the spacing of the ratchet teeth of said second dial plate, guide means on said sheet at the center of said depression providing bearing portions about which said dial plates may rotate, said

guide means and said cam plate having cooperating portions to prevent rotation of the cam plate, means for holding said plates assembled in the depression including spring means whereby the plates are yieldingly pressed together, and detent means on the cam plate and the second dial plate for releasably resisting rotation of the second dial plate, means cooperating with the ratchet teeth of the first named dial plate to ro-

tate it, and a pawl on the first named dial plate cooperating with the teeth of the second dial plate and with said cam to advance the second dial plate after a predetermined advance by the 5 first named dial plate.
